UNITED STATES PATENT OFFICE.

FRANCIS M. BAKER, OF FOND DU LAC, WISCONSIN, ASSIGNOR OF ONE-FOURTH TO PAUL J. ZEIDLER, OF LOMIRA, WISCONSIN.

HYDROCARBON-BURNER.

SPECIFICATION forming part of Letters Patent No. 717,795, dated January 6, 1903.

Application filed July 25, 1901. Serial No. 69,689. (No model.)

To all whom it may concern:

Be it known that I, FRANCIS M. BAKER, a citizen of the United States, and a resident of Fond du Lac, in the county of Fond du Lac and State of Wisconsin, have invented a new and Improved Hydrocarbon-Burner, of which the following is a full, clear, and exact description.

This invention relates to a hydrocarbon-burner analogous in some respects to that previously patented by me June 5, 1900, Serial No. 651,226.

This specification is a specific description of two forms of the invention, while the claims are definitions of the actual scope thereof.

Reference is to be had to the accompanying drawings, forming a part of this specification, in which similar characters of reference indicate corresponding parts in all the views.

Figure 1 is a vertical section of the apparatus. Fig. 2 is a horizontal section on the line 2 2 of Fig. 1. Fig. 3 is a similar view on the line 3 3 of Fig. 1, and Fig. 4 is a sectional view of a modification.

5 indicates the oil-reservoir, which may be double-walled, if desired. The reservoir is supplied with a feed-opening 6, commanded by a screw-cap 7.

8 indicates guide-rods in the reservoir, between which a float 9 is vertically movable. To this float is attached an index-rod 10, which when the screw-cap 7 is removed will move upward with the float through the opening 6. The cap 7 normally holds the float and rod downward; but the instant the cap is removed the rod will rise, and thus indicate the level of the oil within the reservoir. The reservoir has a nipple 11 in its top, in which is screwed a thimble 12. This thimble has a tube 14 and a disk 15 suspended rigidly therefrom. The disk is disposed horizontally, and the tube extends vertically and merges into a retort 16, into which extends a wick 17. This wick projects downward through the thimble 12 and into a tube 18, which extends down into the reservoir 5.

19 indicates a rod or strip of metal which extends alongside of the wick 17 throughout the entire length thereof, thus separating the wick at one point from the interior walls of the tubes 18, 14, and 16 and providing a pas-

sage or space through which gases may pass from the reservoir 5 into the retort. The retort 16 has a discharge-orifice 20 for the gases generated therein. Sustained on the disk 15 is a cylindrical sleeve 21, which extends vertically and incloses the retort. The sleeve is orificed at its lower portion, as indicated at 22, so as to permit the free entry of air into the sleeve. The top of the reservoir 5 sustains a foraminated cylindrical or barrel-shaped casing 23, which is held rigidly in place and formed with an orifice 24 opposite one of the orifices 22 in the sleeve 21. This orifice 24 enables the cup 25 to be reached for the purpose of filling it with oil and permitting the ignition thereof. The cup 25 is fastened to the tube 14 immediately below the retort 16.

Fitting loosely over the sleeve 21 is a collar 26, having spiral threads 27 thereon. These threads 27 respectively engage with projections 28 on the sleeve 21, so that by turning the collar 26 it will be raised or lowered on the sleeve. Sustained rigidly on the collar 26 by means of brackets 29 is a burner-base 30. The brackets 29 are extended upward above the base, as indicated at 31, so as to form sustaining devices for the chimney 32. Carried rigidly by the burner-base 30 is the tubular section 33 of the mixing-chamber, said chamber being made up of the section 33 and a tubular section 34, sustained rigidly on the retort 16 and fitting loosely within the section 33, so that said latter section is capable of moving up or down on the section 34, which always stands rigid with the retort and reservoir. Above the mixing-chamber is arranged the burner 35, which is preferably used in connection with an incandescent mantle 36, sustained properly by a rod 37, as usual. Fastened to the retort 16 and projecting upward through the sections 33 and 34 of the mixing-chamber and through the burner 35 is a rod 38.

The rod 38 is adapted to be heated by the flame of the burner and to transmit the heat thereof to the retort 16, whereby to heat it and cause the generation of gas therein. The wick 17 works by capillary attraction and feeds the oil into the retort. To start the burner, the cup 25 should be filled with oil

and the oil then ignited, thus primarily heating the retort. This will cause the generation of gas, and as the gas passes out of the opening 20 it may be ignited at the burner 35.

5 The parts being in the position shown in Fig. 1, the upper portion of the rod 38 will be subjected to the action of the heat and it will transmit the heat to the retort, so that the operation of the lamp is thus continued, notwithstanding that the oil may have burned out from the cup 25. It is obvious, of course, that the retort 16 may be primarily heated by means other than by burning oil in the cup 25—for example, a blow-lamp or analogous device. Should it be desired to stop the operation of the lamp, the base 30 should be turned, causing the threads 27 of the collar 26 to act on the studs 28. This will elevate the parts 26, 30, 33, and 35 with respect to the sleeve 21, retort 16, and the mixing-chamber section 34, and the burner will be raised above the upper end of the rod 38. The heat of the burner will then be no longer transmitted through the rod 38, and the retort 16 will become cool. Thus the generation of the gas therein will be arrested and the flame of the lamp will fail.

In Fig. 4 I have shown the same principle embodied in a torch or blow-lamp which may be used for various industrial purposes and which also may be used in connection with the illuminating-lamp shown in Fig. 1—that is to say, as a means of primarily heating the retort 16 in said view.

35 In Fig. 4 the tube 14^a rises from the reservoir 5^a and carries the wick 17^a. 16^a indicates a chamber serving as the retort, and 35^a indicates the burner-tube, which is fastened rigidly to the walls of the chamber 16^a. Within the tube 35^a are the telescopic mixing-tubes 33^a and 34^a, of which the latter is fastened rigidly in the tube 35^a and the former slidably mounted and connected with a finger-rod 39, by which it may be moved longitudinally in the tube 35^a. By heating the chamber 16^a with a match or any other means gas will be generated therein, and this gas will flow into and through the tubes 33^a and 34^a to be consumed at the mouth of the mixing-tube 33^a. Now should the mixing-tube 33^a be drawn back to the position shown in the drawings the flame will come partly within the burner-tube 35^a and heat the same. The burner-tube 35^a thus provides a continuous metallic heat-conductor from the igniting-point of the burner back to the retort 16^a, and the heat of the retort will be kept up continuously. To stop the flame, the section 33^a of the mixing-tube should be moved forward so as to project beyond the end of the burner-tube 35^a. The burner-tube being no longer in contact with the flame it will no longer transmit the heat thereof to the retort 16^a. The result of this will be the cessation of the generation of gas or vapor in the retort and the consequent failure of the flame of the lamp.

Various changes in the form, proportions, and minor details of my invention may be resorted to without departing from the spirit 70 and scope of my invention. Hence I consider myself entitled to all such variations as may lie within the scope of my claims.

Having thus described my invention, I claim as new and desire to secure by Letters 75 Patent—

1. The combination of a retort, a mixing-chamber formed of telescopic sections, a burner, a heat-conductor for conducting the heat of the burner to the retort, and means 80 for moving one of the sections of the mixing-chamber on the other to cause the heat-conductor to be unaffected by the heat of the burner, as set forth.

2. The combination of a reservoir, a retort, 85 a wick for conducting the fuel from the reservoir to the retort, a mixing-chamber formed of telescopic sections, a burner, a heat-conductor for conducting the heat of the burner to the retort, and means for moving one of 90 the sections of the mixing-chamber on the other, to cause the heat-conductor to be unaffected by the heat of the burner, as set forth.

3. The combination of a retort, a mixing-chamber, a burner above the mixing-chamber, 95 a heat-conductor secured to the retort and extending up through the mixing-chamber into the burner, and means for relatively moving the burner, and heat-conductor for the purpose specified, said means comprising two 100 members having threaded connection with each other, as set forth.

4. The combination of a reservoir, a retort, means for conducting the fuel from the reservoir to the retort, a mixing-chamber, a burner above the mixing-chamber, a heat-conductor carried by the retort and extending up through the mixing-chamber into the burner, and means for vertically adjusting the burner, as and for the purpose set forth. 110

5. The combination of a retort, a heat-conductor secured to the retort and projecting above the same, and a burner into which the heat-conductor normally projects, said burner being adjustable vertically above the upper 115 end of the heat-conductor, as and for the purpose set forth.

6. The combination of a reservoir, a retort communicating therewith, a sleeve rigidly sustained on the reservoir and having a projection, a collar fitted loosely on the sleeve and having a thread whereby the collar may be raised and lowered on the sleeve, a burner sustained on the collar, and a heat-conductor attached to the retort and extending into the 125 vicinity of the burner, for the purpose specified.

7. The combination of a reservoir, a retort sustained thereon, means for conducting the fuel from the reservoir to the retort, a heat-conductor attached to the retort, a sleeve mounted on the reservoir and inclosing the retort, a collar having a threaded connection with the sleeve to raise or lower the collar, a 130

burner-base sustained on the collar, a burner carried by the base, and a mixing-chamber formed of telescopic sections attached respectively to the retort and burner.

5 8. The combination of a reservoir, a burner movable relatively thereto, a retort, a heat-conductor attached to the retort and extending into the vicinity of the burner, and a mixing-chamber through which the heat-conductor extends into the burner, the said chamber being formed of telescopic sections respectively connected with the burner and retort.

9. In a hydrocarbon-burner, the combination with a retort, of a mixing-chamber formed 15 of telescopic sections, the lower one of which is secured to the retort, a burner carried by the upper section of the mixing-chamber, a rod carried by the retort and extending up through the mixing-chamber and the burner, 20 and means for moving the upper section of the mixing-chamber, as set forth.

10. In a hydrocarbon-burner, the combination of a retort, a mixing-chamber formed of telescopic sections, the lower one of which is 25 secured to the retort, a burner carried by the upper section of said chamber, a rod carried by the retort and extending through the mixing-chamber and normally projecting into the burner, a sleeve surrounding the retort, 30 a collar adjustably mounted on the sleeve,

and a burner-base carried by the collar, as set forth.

11. In a hydrocarbon-burner, the combination of a retort, a cup below the retort, a mixing-chamber formed of telescopic sections, a 35 burner carried by the upper section of the mixing-chamber, a rod secured to the retort and extending up through the mixing-chamber and burner, and means for moving the upper section of the mixing-chamber upward, 40 as set forth.

12. A hydrocarbon-burner, comprising a retort, a cup below the retort, a mixing-chamber formed of telescopic sections, a burner carried by the upper section of the mixing- 45 chamber, a rod secured to the retort and extending up through the mixing-chamber and burner, a perforated sleeve surrounding the retort and having an opening in one side, a 50 collar adjustably mounted on the sleeve, and a burner-base carried by the collar, as set forth.

In testimony whereof I have signed my name to this specification in the presence of two subscribing witnesses.
